CLOTHES POLE SUPPORT

George A. Yokich, Tazewell County, Ill.
(528 Henrietta St., Pekin, Ill. 61554)

Filed Oct. 12, 1966, Ser. No. 4,253

Term of patent 14 years

(Cl. D54—1)

FIG.1

I claim:

The ornamental design for a clothes pole support, as shown.
